(57) **CLAIM**

The ornamental design for a cabinet handle, as shown and described.

DESCRIPTION

FIG. 1 is a perspective view of the cabinet handle; FIG. 2 is side view of the cabinet handle of FIG. 1, with the other side being a mirror thereof; FIG. 3 is a top view of the cabinet handle of FIG. 1; FIG. 4 is a front view of the cabinet handle of FIG. 1; FIG. 5 is a bottom view of the cabinet handle of FIG. 1; and, FIG. 6 is a rear view of the cabinet handle of FIG. 1. The broken lines shown in the figures are included for the purpose of illustrating environment and form no part of the claimed design.
